[57] CLAIM

The ornamental design for a back pack type cooler carrier, as shown and described.

DESCRIPTION

FIG. 1 is a perspective view of a back pack type cooler carrier in accordance with our design;

FIG. 2 is a back elevation view of the back pack type cooler carrier shown in FIG. 1; and,

FIG. 3 is a side elevation view of the left side of the back pack type cooler carrier shown in FIG. 1, the opposite side being identical.

FIGS. 2 and 3 are drawn in reduced scale.
